TIME DELAY RELAY

Merritt Van Valkenburgh, Upper Nyack, N. Y.,
assignor to M. H. Rhodes Incorporated, Hartford, Conn., a corporation of Delaware

Application March 5, 1952, Serial No. 274,910

10 Claims. (Cl. 200—97)

1

This invention relates to a relay having switch means, electromagnetic means associated with the switch means, and a timer device for delaying the operation of the switch means.

The aim of the invention is to provide a relay of this character having various features of novelty and advantage and which is particularly characterized by its adaptability to a wide variety of uses; by its flexibility in use in that it is capable of operation on direct or alternating currents at various voltages to control circuits of various sorts for various time cycles; by its dependability and accuracy in operation under widely varying conditions and influences to which it may be subjected such as extreme temperature changes, vibration, shock, etc.; by its ability to stand up under hard service; by its compactness, and by its simplicity in construction and arrangement and its economy in manufacture.

Other objects will be in part obvious and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the accompanying drawings, wherein I have shown two embodiments which the present invention may take:

Figure 1 is an elevational view looking towards one side of a relay constructed in accordance with one embodiment of the invention, the cover of the casing being in longitudinal section;

Fig. 2 is a view looking at the right hand end of the relay as seen in Fig. 1, the end of the cover of the casing being broken away;

Fig. 3 is a view similar to Fig. 1 but looking at the other side of the relay;

Fig. 4 is a view similar to Fig. 2 but looking at the other end of the relay;

Figs. 5, 6, and 7 are horizontal sectional views taken through the relay, these views being respectively taken on substantially lines *a—a*, *b—b*, and *c—c* of Fig. 1;

Fig. 8 is also a horizontal sectional view through the relay, this view being taken substantially on line *d—d* of Fig. 4;

Fig. 9 is a partial vertical sectional view, the same being taken on line *e—e* of Fig. 4;

2

Fig. 10 is a detail view of the switch arm and the cam assembly for controlling the same as viewed from below;

Fig. 11 is a detail view of the ratchet mechanism associated with the time device and as viewed from below;

Fig. 12 is a detail view showing the stem of the armature of the solenoid and parts associated therewith;

Fig. 13 is a view similar to Fig. 1 but showing another embodiment of the invention, the casing and certain other parts being omitted;

Fig. 14 is a lefthand end view of the structure shown in Fig. 13;

Fig. 15 is a top plan view thereof;

Fig. 16 is a horizontal sectional view taken substantially on line *16—16* of Fig. 14;

Fig. 17 is a horizontal sectional view taken substantially on line *17—17* of Fig. 13, the knockoff pin *110* being shown in position to provide a maximum time cycle;

Fig. 18 is a detail view of the ratchet mechanism shown in Fig. 16 but as viewed from below; and

Fig. 19 is a view similar to Fig. 17 but showing the pin *110* adjusted to a position where a shorter time cycle is obtained.

As will be seen from the accompanying drawings, my improved relay comprises generally one or more solenoids or magnets, a single solenoid *A* being shown in the present instance, and switch means *B* controlled by a cam assembly *C* which is controlled by the solenoid and a timer device *D* in such manner that there is a time delay be-

tween the influencing of the solenoid and the opening or closing of the switch means. In the embodiment shown in Figs. 1 to 12, the cam assembly *C* is turned in one direction on the impulse stroke of the armature to open the switch and is turned in the opposite direction by a spring associated with the armature for moving the latter on its return stroke when the solenoid is de-energized. This arrangement, however, is shown by way of exemplification, it being understood that the switch may be closed on the impulse stroke of the armature and opened on its return stroke thereof and that the timer device may be effective for delaying operation of the switch following the impulse stroke of the armature.

Referring to the embodiment shown in Figs. 1

to 12, the instrumentalities A, B, C and D may be enclosed in a housing or casing E which, in the present instance, includes a base 15 and a box-like cover 16. The base and cover may be made of suitable insulating material, such as plastic. The various specified mechanisms or devices are carried by a suitable chassis secured to the base 15. While this chassis may take any suitable form, it is here shown as comprising a rectangular frame 17 within which the coil 30 of the solenoid is mounted, a bracket 18 secured to one end of the frame 17 and forming, in part, a support for the cam assembly C and the timer device D; and a bracket 19 secured to the top of the frame 17 and to which the boxlike cover 16 is secured as by means of a screw 20. The margin of the base 15 is rabbeted as at 21 so as to closely receive the lower edge of the cover and thus form a substantially dustproof joint. Arising from one longitudinal edge of the base 15 is an upstanding flange or wall 22 to which is secured the various electrical terminals associated with the solenoid and the switch means. One side wall of the cover 16 has an opening for accommodating this flange 22 and the abutting edges of the opening and flange are complementarily rabbeted as at 23.

Referring now more specifically to the solenoid, the same is here shown as comprising a coil 30 having a tubular core 31 secured in and extending beyond the forward end wall 32 of the frame 17. Fitting in the other end of the core is a plug 33 which is secured to the other end wall 34 of the frame 17. The frame 17 is secured to the base 15 by bolts 35. The solenoid has an armature 36 slidably fitting in the core 31, and this armature has a stem 36' extending beyond the open end of the core. About this stem and adapted to abut against the open end of the core is a collar 37. About the stem 36' and interposed between the collar 37 and a second collar 38 is a coiled spring 39 for returning the armature to the normal position shown in the drawings upon de-energization of the solenoid. The collar 38 is slidably mounted on the stem 36'. A pin 41 is associated with the ratchet mechanism of the timer device D and the cam assembly C, as hereinafter explained more in detail. The lower end of this pin engages between the collars 38 and 40. The collar 40 forms an abutting shoulder for the pin and abuts against a nut 42 adjustably screwed onto the free threaded end of the stem 36'. The body portion of the armature and the stem 36' thereof may be chromium plated and polished so that the armature may slide within the core and the collars may relatively slide with respect to the stem without sticking or undue friction in the absence of a lubricant. By arranging the collars 39 and 40 on the stem 36' with the pin 41 engaging therebetween, the necessity of providing a guiding support for the free end of the stem is eliminated, the armature may turn about its axis without affecting the operation of the apparatus, and lubrication is eliminated, all of which provides a very simple, effective structure permitting the relay to function over wide temperature variations. It has been found that the mechanism will operate with substantially like accuracy between temperatures ranging from minus 76° to plus 185° F., and this would not be possible if the contacting sliding surfaces were lubricated as the consistency of the lubricant would change depending upon the temperature to which it would be subjected. There may also be

slidably mounted on the stem of the armature a stop sleeve or collar 44, the purpose of which will be later described. The ends of the coil 30 are connected to terminals 43 carried by the flange 22.

Referring now to the switching means B, the same comprises, in the present illustrative disclosure, a switch arm 50 positioned between a pair of spring fingers 51, 52. The switch arm 10 and fingers are secured to a laminated insulator block 53 which is secured to the base 15 as by means of a bracket 53' and bolts 54. The switch arm, adjacent its free end, carries a double contact 55 adapted to alternately engage contacts 56 and 57 respectively secured to the fingers 51 and 52 adjacent the free ends thereof. The finger 51, the switch arm 50, and the finger 52 may be respectively connected to the terminals 58, 59, and 60 of the power circuit.

The switch arm is moved from one position to the other by the cam assembly C acting through a lever or arm 61 which is pivoted at one end on a pivot 62 fixed to and depending from the bracket 18. The lever 61, at its free end, has a pair of depending cylindrical studs 63 formed of insulating material, and these studs are in straddling relation to the free end of the switch arm 50 beyond the contact 55 carried thereby. Depending from the lever 61 and located between the ends thereof is a follower pin 64 which is resiliently urged towards the periphery of the cam assembly C by a spring 65 coiled about the pivot pin 62 and having its opposite ends respectively anchored to the lever 61 and the bracket 18.

The cam assembly C comprises a cam disk 70 fixed to a vertical shaft 71, and a supplemental disk 72 journaled on the shaft 71 for limited rotary movement with respect to the disk 70. The shaft 71 is journaled in a vertical sleeve 67 carried by the bracket 18. Fixed to the upper end of this shaft is an arm 68 in which the pin 41 is fixed and which pin, as previously stated, engages between the collars 38 and 40 of the armature 36. In order to permit of lost motion between the disks 70 and 72, the disk 72 has a slot 73 into which extends a pin 74 depending from the disk 70. The disk 70 has a notch with a generally radially extending edge 75 and a cam or sloping edge 76. The disk 72 is of slightly larger diameter than the disk 70 and it has a notch with an edge 77 corresponding to, and adapted to register with, the edge 75 when the pin 64 is engaged in the bottom of the notches, and a generally radially extending edge 78. With this arrangement, when the cam assembly is rotated counterclockwise with respect to Fig. 8 (and which movement, in the present instance, takes place on the impulse stroke of the armature of the solenoid), the cam edge 76 cams the pin 64 outwardly so as to move the contact 55 out of engagement with the contact 56 and into engagement with the contact 57, and then the pin engages against the periphery of the disk 72. On reverse rotation of the cam disk 70 (which takes place as the armature is moved to the left in Fig. 7 under the influence of the spring 39) the disk 72 is held stationary (due to the arrangement of the pin 64 against the periphery thereof) until the pin 74 engages the other end of the slot 73 and then the two disks rotate together until the pin 64 rides off of the periphery of the disk 72 and into the notch in the disk 70 to the position shown in Figs. 8 and 10, whereupon contact 55 is moved out of engagement with con-

tact 56 and into engagement with contact 57. Referring now to the timer device D, the same is shown, for purposes of exemplification, as comprising a clock mechanism provided with an arbor 85 journaled in bearings provided in frame plates 86 and 87 maintained in spaced relation by pillars 88. The arbor is in general axial alignment with the shaft 71. Fixed to the arbor is a main gear 89 which is connected through a gear train 90 to the escapement wheel 91. Cooperating with a teeth of this escapement wheel are the pins 92 of the usual pallet wheel 93 whereby the speed at which the clock arbor is driven in one direction is controlled. Fixed to the arbor 85, and located beneath the lower frame plate 87, is a ratchet wheel 95. Cooperating with the serrated edge of this ratchet wheel are two spring pressed pawls 96 (see Fig. 11) carried by an arm 97 journaled on the lower end of the arbor 85. In the embodiment shown in Figs. 1 to 12, the pawl carrying arm 97 has between its ends a hole 98 through which closely extends the upper end of the pin 41 so that the pawl carrying arm 97 and the arm 68 swing substantially in unison.

The operation of the device shown in Figs. 1 to 12 will be readily understood from the foregoing description taken in connection with the following explanation: It may be assumed that when the parts are in the position shown in the drawings, the switch means B is in closed condition and no current is passing through the coil of the solenoid. Upon energization of the solenoid, the armature 36 thereof will move on its impulse stroke, that is, towards the right referring to Figs. 6 and 7, and, due to the engagement of the collar 40 with the pin 41, the cam assembly will be rotated counterclockwise, with respect to Fig. 8, with the result that the follower pin 64 will ride out of the notches of the disks 70 and 72 of the cam assembly thereby moving the switch arm 50 from the position shown in Fig. 8 to a position where the contacts 55 and 56 are engaged. At the same time, the pawl carrying arm 97 is moved on its inoperative stroke, that is, counterclockwise with respect to Fig. 6 and clockwise with respect to Fig. 11, and during such movement, the pawls will ratchet over the ratchet wheel 95. These parts will retain these positions until the solenoid is deenergized. Upon stoppage of the armature during its operative stroke, there is a tendency for the pin 41, the arm 68, the cam assembly, and the ratchet lever 97 to continue to move due to their momentum, and if this were allowed, overtiming would result and the timing would vary widely. In order to prevent this, the stop collar 44 is provided on the armature stem between the collars 37 and 38. This stop collar is of such length that, when it is engaged between the collars 37 and 38, the collar 38 will be spaced from the collar 40 at a distance equal to the diameter of the end of the pin 41 engaging therebetween. That is to say, when the armature is in its inner or righthand position, the collars 38 and 40 will bear the same position relative to one another that they do when the armature is in the outer or lefthand position shown in Figs. 7 and 12. Upon de-energization of the solenoid, the spring 39 associated with the armature thereof will move the armature on its return stroke, that is, towards the left referring to Figs. 6 and 7, and, due to the fact that this spring urges the collar 38 against the pin 41, the cam assembly is driven in a clockwise direction, with respect to

Figs. 6 to 8. The speed at which the cam assembly is thus driven is, however, controlled by the timer device so that there is a predetermined time delay between the de-energization of the solenoid 5 and the operation of the switch. It is observed that on the return stroke of the armature, the spring 39 drives the clock train through the collar 38, pin 41, pawl carrying arm 97, pawls 96, and the ratchet wheel 95, and the escapement, comprising the gear train 90, the escapement wheel 91 and the pallet wheel 93, determines the speed at which the clock mechanism is driven.

Referring now to the embodiment of the invention shown in Figs. 13 to 19, inclusive, the arrangement is similar to that just described but provision is made for changing the time cycle at will. In these figures, the solenoid is shown only in part, and the cam assembly and the switch means are not illustrated, it being understood that these instrumentalities may be similar to those illustrated in Figs. 1 to 12. Where the parts correspond to similar parts of the previous embodiment, like reference numerals are employed but the numerals are primed.

In this latter embodiment of the invention, the pin 41', instead of passing through an opening in the ratchet pawl carrying arm 97' is adapted to engage that edge of the arm which faces away from the coil 30'. The crank arm 68', which carries the pin 41', is provided at its free end with a tooth 100 with which cooperates a latch 101 pivotally carried by the arm 97'. The crank arm 68' is fixed to the vertical shaft 71', the lower end of which carries the cam assembly as in the preceding embodiment. The lower end of the pin 41' engages between the collars 38' and 40' on the stem 36'' as in the preceding embodiment. The timer device D' is similar to that previously described.

The latch 101 is pivoted on the lower end of one of the studs 102 employed for pivoting one of the pawls 96' to the arm 97'. This latch is in the form of a bell crank, one arm 104 of which is provided with a tooth 105 which is adapted to cooperate with the tooth 100 on the crank arm 68' as shown most clearly in Fig. 17. On the inner edge of the arm 104 is an extension 106 adapted to engage a lug 107 depending from the arm 97' for the purpose of limiting the inward swinging movement of the latch. The other arm 108 of the latch is adapted to engage an adjustable knock-off pin 110 so as to release the latch from the crank arm at the termination of the selected time period. The latch is normally urged clockwise with respect to Fig. 17 by a spring 111.

The latch trip or knock-off pin 110 is carried by an indicator arm 112 which is pivoted to a stud 113 on an indicator plate 114. The plate 114 is secured to the top plate 86' of the timer mechanism, and the pivot stud 113 is in alignment with the arbor 85' of the timer. The plate 114 is offset upwardly between its ends so as to accommodate between itself and the plate 86' the indicator arm. One edge of the plate 114 is provided with a scale which, in the present instance, is formed by notching the plate as at 115. The outer end of the indicator arm is provided with a pointer 116 for cooperation with this scale. For the purpose of locking the indicator arm in any desired position of adjustment, the plate 114 is provided with an arcuate slot 117 which accommodates a lock screw or bolt 118 carried by the indicator arm.

The operation of the device shown in Figs. 13

to 18, inclusive, is briefly as follows: Figs. 13 to 18, inclusive, show parts in the normal position corresponding to the position of the parts shown in Figs. 3 to 8, inclusive, of the first embodiments. The knock-off pin 110 is shown in position to provide the maximum time cycle, pointer 116 or indicator arm 112 being set at the last lefthand division on scale 115 (see Fig. 15). In this position, knock-off pin 110 has no influence on latch 101 so that the tooth 105 on the latch remains in engagement with the tooth 100 on arm 68' as shown by full lines in Fig. 17. In this relationship, upon energization of the solenoid, the armature thereof will move to the right and collar 40' will move pin 41' to the right so that the cam assembly will be rotated to move contact 55 out of engagement with contact 56 as in the preceding embodiment. At the same time, due to the engagement of pin 41' against the opposed edge of the pawl carrying arm 97', this arm will be moved to the right, referring to Fig. 16 and the ratchet pawls 96' will ratchet over the wheel 89'. Upon de-energization of the solenoid, the spring 39' will move the collar 38' to the left, urging pin 41' on crank 68' clockwise and through engagement of tooth 100 on the latter with tooth 105 on latch 101 inducing similar rotation of pawl carrying arm 97' at a rate governed by the timer device through the engagement of pawls 96' with ratchet wheel 89' on the latter assembly. Since in the adjustment shown in Figs. 16 and 17, knock-off pin 110 is so far to the left that it has no influence upon latch 101 before the clockwise rotation of arm 68' and associated cam assembly has reached the normal position allowing contact 55 to move back out of engagement with contact 56 and into engagement with contact 57 again, tooth 105 on latch 101 will remain in engagement with tooth 100 on arm 68' throughout the entire clockwise movement of the latter and thus with this adjustment the rate of clockwise movement of arm 68' and its associated cam assembly will be governed by the timer device throughout its complete operating arc.

Referring now to Fig. 19, the knock-off pin 110 is shown in a position corresponding to an intermediate adjustment of the pointer 116 on the scale 115 so that the time cycle is less than maximum. In this figure, the arm 68' and the latch 101 are shown by dash lines in their normal positions. Further, these parts are shown by full or solid lines in the positions which they have at the end of the timing cycle, that is, just as the tooth 105 on the latch is disengaged from the tooth 100 on the arm 68' during the movement of the armature under the influence of the spring 39', the solenoid having been de-energized. Starting with the parts in their normal positions, upon energization of the solenoid, the armature thereof will move to the right causing the collar 40' to move the pin 41' to the right so that the cam assembly will be rotated to close the switch as in the preceding embodiment. As the pin 41' moves to the right, the arm 68' is moved counterclockwise, and during such movement, the cam surface 119 on the back of the tooth 110 will engage the cam surface 120 on the back of the tooth 105 so that the latch 101 will be cammed out and then, when the teeth are in alignment, the tooth 105 on the latch will snap quickly and positively into engagement with the tooth 100 on the arm 68'. Following this, the pin 41' will immediately strike the opposed edge of pawl carrying arm 97', whereupon this arm will move to

the right and ratchet pawls 96' will ratchet over the wheel 89'.

Still referring to Fig. 19, upon de-energization of the solenoid, the spring 39' will move the crank arm 68' and the pawl carrying arm 97' clockwise as a unit at a rate governed by the timer device in the manner previously described, but with the setting of the knock-off pin shown in Fig. 19, this pin is effective to disengage the latch 101 from the crank arm at an intermediate point in operating arc of the latter, depending upon the selected time cycle, whereupon the spring 39' will drive the arm 68', together with its associated cam assembly, with great rapidity through the remainder of its operating arc to effect the same switch action as previously described.

It will be seen that, upon engagement of the arm 108 of the latch with the knock-off pin, the latch is moved counterclockwise about its pivot 102 until the tooth of the latch is disengaged from the tooth 100 of the arm 68'. During this time, some reaction is transmitted through the latch 101 to the pawl carrying arm 97' (which is free to move counterclockwise as the pawls 96' may ratchet over the ratchet wheel 89') with the result that the arm 97' will move counterclockwise from the dash line position to the dash and dot line position shown in Fig. 19, and the latch 101 will assume the normal position shown in broken lines. In this position, the latch 101 is urged as far as the knock-off pin will allow, clockwise towards the stop 107 by the spring 111. It is obvious that the time cycle may be varied by adjusting the indicator arm 112 and the knock-off pin 110 carried thereby.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a time delay relay, electromagnetic means having an armature provided with a shoulder, a slidable collar on said armature, a spring about said armature and bearing against said slidable collar and arranged to be compressed upon energization of the electromagnetic means and to move the armature outwardly upon de-energization of the electromagnetic means, a switch, a cam controlling said switch, an escapement clock mechanism for controlling the speed of rotation of said cam in one direction, and a pin engaging between said collar and shoulder and operatively connected to said cam and said clock mechanism.
2. In a time delay relay, electromagnetic means having a coil provided with a tubular core and an armature slidably fitting in the core and having a stem extending therebeyond, said armature having a polished plated surface, a collar about said stem and abutting the end of said core, a shoulder on said armature adjacent the free end of said stem, a slidable collar on said stem between said first mentioned collar and shoulder, a spring about said armature between said collars and arranged to be compressed upon ener-

gization of the electromagnetic means to move the armature outwardly upon de-energization of the electromagnetic means, a switch, a cam controlling said switch and rotatable in opposite directions, an escapement clock mechanism for controlling the speed of rotation of said cam in one direction, and a pin engaging between said second mentioned collar and shoulder and operatively connected to said cam and said clock mechanism.

3. In a time delay relay, electromagnetic means having a slidable armature provided with a shoulder, a slidable collar on the armature, a spring about the armature and bearing against said slidable collar and arranged to be compressed upon energization of said electromagnetic means and to move said armature outwardly upon de-energization of the electromagnetic means, a switch, a cam controlling said switch and rotatable in opposite directions, an escapement clock mechanism for controlling the speed of rotation of the cam in one direction, a pin engaging between said shoulder and slidable collar and connected to said cam, an arm connected to said pin, and a pawl and ratchet connection between said arm and said escapement clock mechanism.

4. In a time delay relay, electromagnetic means having an armature provided with a shoulder, a slidable collar on said armature, a spring about said armature and bearing against said slidable collar and arranged to be compressed on inward movement of the armature upon energization of the electromagnetic means to move the armature outwardly upon deenergization of the electromagnetic means, a switch, a cam controlling said switch, an escapement clock mechanism for controlling the speed of rotation of said cam in one direction, a pin engaging between said collar and shoulder and operatively connected to said cam and said clock mechanism, and means for positively limiting the extent of movement of said slidable collar upon inward movement of the armature whereby to prevent overthrow of the cam and clock mechanism.

5. In a time delay relay, electromagnetic means having a coil provided with a tubular core and an armature slidably fitting in the core and having a stem extending therebeyond, said armature having a polished surface, a collar about said stem and abutting the end of said core, a shoulder on said armature adjacent the free end of said stem, a slidable collar on said stem between said first mentioned collar and shoulder, a stop collar on said stem between said first and second collars and arranged to limit the extent of movement of the second mentioned collar when the armature is moved inwardly, a spring about said armature between said first and second mentioned collars and arranged to be compressed upon energization of the electromagnetic means to move the armature outwardly upon de-energization of the electromagnetic means, a switch, a cam controlling said switch and rotatable in opposite directions, an escapement clock mechanism for controlling the speed of rotation of said cam in one direction, and a pin engaging between said second mentioned collar and shoulder and operatively connected to said cam and said clock mechanism.

6. In a time delay relay, electromagnetic means having an armature, a switch, a cam controlling said switch, an arm carried by said cam means, an escapement clock mechanism, ratchet means operatively associated with said escapement mechanism, an arm carried by said ratchet

means, said arms being relatively movable with respect to each other, means actuated by said armature for moving said arms in one direction upon energization of the electromagnetic means, 5 latch means carried by one arm and interengaging the other arm to effect movement of said arms in unison in a direction opposite to said one direction upon de-energization of said electromagnetic means and under control of said escapement mechanism, and means for tripping said latch means at a selected point in their said opposite direction movement to disengage said arms so that continued movement of said cam arm by the armature can ensue free from control of said escapement mechanism.

7. In a time delay relay, electromagnetic means having an armature movable between two positions, a switch having a member movable between two positions, a cam for controlling said switch 20 member, an operative connection between said armature and cam through which the latter is rotated in one direction when said armature is moved into one position, an escapement clock mechanism for controlling the speed of rotation 25 of said cam in the opposite direction during movement of said armature to its other position, spring means for driving said clock mechanism and arranged to be placed under compression by said armature when said electromagnetic means 30 is energized, a disengageable latch connection between said clock mechanism and cam, and adjustable trip means for said latch connection.

8. In a time delay relay, electromagnetic means having an armature movable between two positions, a switch, a cam for controlling said switch, an operative connection between said armature and cam and through which the latter is rotated in opposite directions upon energization and de-energization of said electromagnetic means, an 35 escapement clock mechanism for controlling the speed of rotation of said cam in one direction, a pivoted arm operatively associated with said armature and movable in opposite directions upon energization and de-energization of the 40 electromagnetic means, a ratchet associated with said clock mechanism, a pawl carried by said arm and cooperating with said ratchet, a latch pivoted to said arm and engageable with said operative connection upon movement of the armature in one direction, and adjustable means for tripping said latch.

9. In a time delay relay, electromagnetic means having an armature provided with a shoulder, a slidable collar on said armature, a switch, a cam controlling said switch and having a crank arm connected thereto, a tooth on said arm, a pin carried by said arm and engaging between said collar and shoulder, an escapement clock mechanism for controlling the speed of rotation of said cam in one direction, a pivoted arm, a ratchet associated with said clock mechanism, a ratchet pawl carried by said pivoted arm and cooperating with said ratchet, said pin being arranged to engage said pivoted arm to move the same in 55 a direction in which the pawl will ratchet over said ratchet, a pivoted latch carried by said pivoted arm and arranged to engage said tooth, an adjustable pin for disengaging said latch from said tooth, and spring means for moving said collar outwardly and said pivoted arm upon outward movement of said armature.

10. In a time delay relay, electromagnetic means having an armature movable between two positions, a switch having a member movable between two positions, a rotatable shaft, a cam

11

on said shaft for controlling said switch member, a crank arm secured to said shaft, a pin carried by said crank arm and operatively connected to said armature and through which said shaft and cam are rotated in one direction when said armature is moved into one position, an escapement clock mechanism for controlling the speed of rotation of said cam in the other direction, a pivoted arm operatively connected to said pin and through which said crank arm is moved, a 10 ratchet associated with said clock mechanism, a pawl carried by said pivoted arm and arranged to ratchet over said ratchet when said armature is moved into the first mentioned position and

5

12

adapted to positively engage the ratchet when the armature is moved to its other position, and spring means for driving said clock mechanism and arranged to be placed under compression by said armature when said electromagnetic means is energized.
